UNITED STATES PATENT OFFICE.

AMOS PIERCE SMYTHE, OF OLETHA, TEXAS.

DESIGN FOR A HUB-WRENCH.

SPECIFICATION forming part of Design No. 35,450, dated December 17, 1901.

Application filed November 12, 1901. Serial No. 82,056. Term of patent 14 years.

To all whom it may concern:

Be it known that I, AMOS PIERCE SMYTHE, a citizen of the United States, residing at Oletha, in the county of Limestone and State of Texas, have invented and produced a certain new and original Design for Hub-Wrenches; and I do declare the following to be a full, clear, and exact description of the invention, such as will enable others skilled in the art to which it appertains to make and use the same.

The invention relates to a new and original design for a hub-wrench; and it consists of the design of the configuration shown in the accompanying drawing, in which I have illustrated my invention in perspective.

The leading feature of the design comprises

an angular socket-head 1, having in its free edges annular recesses 2 and 3 of different areas and arranged between two diverging arms 4, which cross the head on its rear side and which have their free ends one beveled, as shown at 5, and the other formed with an angular extension 6.

What I claim is—

The design for a hub-wrench, as herein shown and described.

In testimony whereof I have hereunto set my hand in presence of two subscribing witnesses.

AMOS PIERCE SMYTHE.
